United States Patent Office

Des. 192,863
Patented May 22, 1962

192,863

FIREWOOD PACKAGE

James H. Berry, Eureka, Calif., assignor to Heird Lumber
Co., Inc., Eureka, Calif.

Filed Mar. 21, 1961, Ser. No. 64,421

Term of patent 14 years

(Cl. D32—1)

Fig. 1.

Fig. 2.

Fig. 3.

FIG. 1 is a top perspective view of a firewood package, showing my new design;

FIG. 2 is a side elevational view thereof; and

FIG. 3 is an end elevational view thereof.

I claim:

The ornamental design for a firewood package, as shown.
